INTERNAL GRINDER

Joseph Baldyga, Roseville, Mich.

Application September 17, 1954, Serial No. 456,688

2 Claims. (Cl. 51—90)

My improvement pertains to a grinder adapted for operative application to circular apertures in solid objects of such a nature as blocks or plates.

The improvement, in its practical embodiment, consists of a device which may be mounted upon framework or a stand which supports a motor for the operation of some of the parts of the grinder and which framework is provided with means for support and for adjustment of the position of the object to which the grinder is applied, the means including what is known as a longitudinal and a cross-feed.

I shall now describe my improved grinder with reference to the accompanying drawings in which:

Fig. 1 is a perspective view of the grinder, the view including, in perspective, the object to which the grinder is operatively applied;

Fig. 2 is a top elevational view of the grinder, with parts shown in sectional views;

Fig. 3 is a sectional view on line 3—3 of Fig. 2;

Fig. 4 is a sectional view on line 4—4 of Fig. 3;

Fig. 5 is a front view of a member containing a circular hole, the view disclosing the position of the grinding wheel with respect to the inner surface of the hole.

Similar numerals refer to similar parts throughout the several views.

The stand upon which my attachment is mounted is generally identified by numeral 10. The grinder, which is generally identified by numeral 11, includes a substantially cylindrical housing 12 provided with a radially-extending holder 13. The latter contains a cavity 14 for engagement with an arm 15 which fits into the socket but is a part of the stand 10.

The boss arm includes an axially-disposed, tapering member 16 terminating with a threaded stub 17, as shown in Fig. 1. The holder is, preferably, split longitudinally, as shown at 19, but is provided with two radially-disposed lugs 18 straddling the split. Each of the lugs has an opening 18a in alignment with the opening in the adjoining lug, the openings serving for reception of a bolt 9 which, in conjunction with a nut 9a, serves to tighten the holder for a better frictional engagement with said arm 15.

The housing 12 has the form of a thick-walled cylinder which is open at both ends. Axially disposed therein is a rotor 21 of a diameter-to-fit into the axial space of the housing, with the exception of the front portion 22. The latter is one end portion of said rotor, its diameter being substantially equal to that of the outer diameter of the housing. The annular surface of said front portion is defined by two parallel ridges 24, the surface therebetween being adapted for application of a driving belt 25 which is operatively connected with an electric motor 26 mounted on top of said holder 13.

As best shown in Fig 3, the rotor is supported at both its ends by ball bearings, the ones at the front portion of the rotor being marked 27, while the ball bearings at the opposite or rear end are marked 28. In accordance with the best practice, the bearings include annular races. The races, mounted within the housing 12, are marked

2

30. The races, carried by the rotor, are marked 30a. At the rear end, the race 30a is secured in its place by means of a ring 31 threaded upon the rear end of the rotor. An analogous ring, 32, is located at the front end of the housing to prevent the displacement of the race 30.

The rotor contains an axial aperture 34 which is open at both ends. Slidably disposed therein is a bar 35 which at its rear abuts a thrust bearing 36 to which I shall refer again.

Secured to the rear end of the housing is a closure including a cup-shaped unit 38 provided with a radially-extending flange 39. The latter is provided with a plurality of holes for application of screws 37 by means of which the closure is connected to said housing. The cup-shaped unit 38 contains an axial bore 40.

Axially mounted upon the cup for rotation thereon is a semispherical knob 41 which also is provided with an axial bore 42. Passing therethrough and through said bore 40 is a propelling screw 43 which at one end is keyed to said knob, as shown at 44, for rotation therewith. A washer 45, threaded upon the screw at the end terminating within the knob, prevents axial movement of said screw inwardly in the direction of bar 35, while an annular fin 46 upon said screw prevents its movement in the opposite direction.

The inner end 47 of the propelling screw 43 is threaded into a sleeve 48 which is adapted to move longitudinally, that is, axially, into said cup 38, but is prevented from rotating about its axis. This is effected by customary slot and key means, of which the key or rib is indicated by numeral 50. The sleeve, at what its inner end, abuts the above-mentioned thrust bearing 36.

The knob 41 is equipped with an annular band 51 bearing a plurality of calibrations for reading against a stationary mark "0," identified by numeral 52.

At the front end the rotor includes, on its face, a diametrically-disposed slideway 60 for engagement with a spindle-carrying mechanism, generally identified by numeral 61. Rearwardly of said slideway, the front portion 22 of the rotor contains a substantially diametrically-extending slot 53 opening outwardly through said slideway, as shown in Fig. 3. Located within the slot is a two-arm crank lever 54 pivotally mounted on a shaft 55 the ends of which are imbedded in the front portion of the rotor. One of the arms 56 of the lever bears against the front end of the bar 35. The other arm 57, called the actuating arm, is directed outwardly, as shown in Figs. 2 and 3.

Rearwardly of the slideway 60 in the rotor, and parallel thereto, are two oblong recesses 62, one on each side of the slideway, as shown in Fig. 4. Each of the recesses contains a coiled spring 63 which, at its lower end, bears against a movable lug 64.

Engaged with the slideway by means of a dovetail member 66, for a diametrical movement thereon and to the axis of the rotor, is a thick disk, indicated generally by numeral 65. The disk is provided with a diametrical slot 66 in alignment with the slot 53 in the rotor, and is defined, at one end, by a transverse wall 67. On each side of the slot in said disk 65, but at points remotely located from said end wall 67, the disk is provided with transverse apertures for reception of screws 68 by means of which the disk is secured to the aforesaid lugs 64. Thus, the springs which at their upper ends, as shown in Figs. 3 and 4, bear against the respective upper walls of recesses 62, urge the disk, by means of said bolts 68, in a downward direction. However, the movement of the disk under the force of said springs in said downward direction is checked by the arm 67 of the crank lever 54.

On its outer face, the disk 65 with a diametrical recess 69, and mounted on said disk for rotation therewith by

being engaged by said recess, is a drum-like housing of a mechanism 61 designed to drive a spindle 70 at one end axially mounted within said housing and carrying at its outer end an abrading member 71.

Air, under pressure, is delivered to said mechanism from a source of supply, such as a compressor, which is not shown, through a tube 72. The tube, as shown in Fig. 3, is threaded into a bore 73 in the housing 12 wherefrom the air is led into an annular groove 74 in the rotor. A passageway 75, within the rotor, leads to the outer face of said rotor, specifically, to a nipple 76. The nipple, in turn, is connected by a flexible tube 77 to another nipple 78 leading to the interior of the mechanism 61 and serving as an inlet port for compressed fluid medium, such as air, by which medium the spindle is to be rotated about its axis.

A screw 79, driven radially through the disk 65 into a frictional contact with the adjoining portions of the member 61, serves to keep said member against movement with respect to said disk.

The manner in which the device operates is as follows:

The object 80 upon which the grinder is to operate is clamped in place upon a supporting member 90 which is a part of the surface grinder 10. The supporting member is elevated to an adjustable position and adjusted laterally and longitudinally with respect to the position of the rotor of my device, which adjustments can be effected by the customary longitudinal and cross feed means with which the stand 10 is equipped. Said means include a horizontal slideway 82 supported on cross-beams 83 for a movement laterally to the length of the slideway. Mounted upon the slideway, for a longitudinal movement thereon, is a slide 84. It is said slide 84 which serves as a base for said supporting member 90. Means which are not shown are provided to move the slideway vertically, all of the movements, vertical and horizontal, being effected by means of screws or racks. As the mechanism is in common use and forms no part of the applicant's improvement, no further description thereof is necessary.

Assuming that the inner surface of the circular aperture 81 in the object 80 is to be ground, the object is shifted towards the spindle till the spindle is in an axial position with respect to said aperture. It will be noted that the diameter of the aperture exceeds that of the diameter of the abrading member 71.

Next, the electric motor 26 may be started to bring about the rotation of the rotor, and compressed air may be admitted to mechanism 61 to bring about the rotation of the spindle 70. Thereupon, the knob 41, is turned manually to rotate the propelling screw 43 and to impart a longitudinal movement, by means of the sleeve 48, to the bar 35 which bears against one arm 56 of the crank lever 54. As the bar pushes against said arm, the opposite arm 57 bears against the cross-wall 67 of the slot in the disk 65 and moves said disk against the tension of the springs 63 diametrically with respect to the adjoining end of the rotor. Because of said shift of the disk, the position of the spindle shifts to an off-center position with respect to the axis of said rotor. The extent of the shift is indicated by calibrations on the annular band 51 on the knob 41, which calibrations are checked against the stationary mark 52 on the flange 39 of the member 38.

Thus, as the rotor is driven about its axis, which is

also the axis of the aperture 81, the spindle, carried with the rotor and carrying the abrading element, rotates in an orbit about said axis.

It will be obvious that some changes may be made in the structure of my device without departing beyond the range of inventive concept disclosed herein. And so, for instance, while I have employed compressed air to operate the spindle 70, said spindle could as well be operated by electric means. And while I have shown the device in conjunction with framework of a surface grinder, it will be understood that it may be used with any suitable framework equipped with means for the adjustment of the position of the object on which the grinder is to operate.

15. What I, therefore, wish to claim is as follows:

1. A grinding device including a stationary housing, a rotor disposed therein, said rotor having an axial bore and a diametrical slot opening outwardly toward one end face, a two-arm lever mounted pivotally within said slot, a bracket mounted on said face for a diametrical movement thereon, the bracket including means for operative engagement with one of said arms, axially-movable means within the bore and bearing against the other arm of the lever, a calibrated knob mounted upon the housing at one end thereof and forming a closure therefor, the knob being operatively connected with the axially-movable means to cause said means to bear against the last-named arm to cause a diametrical shift of the bracket, a spindle-carrying mechanism mounted on the bracket, an abrading element axially mounted on the spindle, motor means to drive the rotor about its axis, and compressed air means to actuate said mechanism to rotate the spindle about its axis.

2. A grinding device including a stationary cylindrical housing, a rotor disposed therein and projecting from said housing at one end thereof, the rotor having an axial bore and being provided at the end projecting from the housing with a diametrical slideway and a slot therein, and being further provided at said end with means for being operatively driven by a motor, a drum-like member connected to the rotor for a sliding diametrical movement upon the outer face of the rotor, a two-arm lever pivotally mounted within said slot, one arm being in operative relation with respect to said member, air-driven motor means within said member, a spindle adapted to be driven by said motor means and axially projecting from said drum-like member, axially movable means within the bore adapted to bear against the other arm of the lever to cause a diametrical shift of the drum-like housing by means of the first-named arm, a calibrated semi-spherical knob covering the other end of the housing and operatively connected to the axially-movable means, and means to admit air to the drum-like member to actuate the motor means therein and to impart a rotary movement to the spindle independently of the rotation of the rotor.
